(57) **CLAIM**

The ornamental design for a nozzle, as shown and described.

DESCRIPTION

FIG. 1 is a front perspective view of the new ornamental nozzle of the present invention.

FIG. 2 is a front view thereof.

FIG. 3 is a right side view thereof.

FIG. 4 is a rear perspective view thereof.

FIG. 5 is a rear view thereof.

FIG. 6 is a left side view thereof.

FIG. 7 is a top view thereof; and,

FIG. 8 is a bottom view thereof.

The exterior surface of the nozzle design is semi-transparent, with semi-transparent ribs separating the exterior surface from the interior.
